UNITED STATES PATENT OFFICE.

OVILA J. VERRETT, OF SYRACUSE, NEW YORK.

ADDRESSING MACHINE.

Application filed December 16, 1925. Serial No. 75,786.

The present invention relates to improvements in printing machines and more particularly to an addressing machine. This application is a continuation in part of the 5 application filed by me under date of December 19, 1924, Serial No. 756,953.

An important object of the invention is to provide an addressing machine, whereby envelopes may be easily and efficiently addressed in such a manner as to save considerable time and labor.

Another object of the invention is to provide means for printing the return address on the envelope simultaneously with the 15 printing of the forwarding address.

Another important object of the invention is to provide an addressing machine of this nature which is simple in construction, inexpensive to manufacture, durable, strong, 20 not likely to easily become out of order, and otherwise well adapted to the purpose for which it is designed.

With the above and numerous other objects in view as will appear as the description 25 proceeds, the invention resides in certain novel features of construction, and in the combination and arrangement of parts as will be hereinafter more fully described and claimed.

30 In the drawings—

Figure 1 is a side elevation of the machine embodying the features of my invention,

Fig. 2 is a longitudinal vertical section 35 therethrough,

Fig. 3 is a top plan view thereof, with the cover removed.

Fig. 4 is an enlarged detail section showing the means for taking an envelope from 40 the envelope hopper,

Fig. 5 is a plan view of the shield plate for the envelope hopper, and

Fig. 6 is a detail view of the friction roller 45 for engaging the envelope to partially eject the same from the hopper.

Referring to the drawing in detail, it will be seen that 5 designates generally a casing having a partition 6 located at the upper portion thereof. The upper portion or 50 cover 8 of the casing 5 has disposed therein an envelope hopper 9 and an address plate hopper 10. A plurality of envelopes 11 are mounted in the hopper 9 and have a weight element 12 thereon. A plurality of address plates 13 are mounted in the hopper 10.

Rollers 14 and 15 are mounted respective-

ly on shafts 16 and 17 journaled through the sides of the casing 5. A pulley 18 is mounted on the end of the shaft 17 and is driven by belt 19 which is trained over a 60 pulley 20 operatively engaged with the pulley 21. A clutch 18' is associated with the shaft 17 and pulley 18. A motor 22 has a pulley 23 on its shaft over which is trained a belt 24 which is also trained over the pulley 21. Thus when the motor is energized, the pulley 15 is in motion. A double-ply belt 25 is trained over the rollers 14 and 15 and also over a roller 26 in the lower intermediate portion of the casing 5. This belt 70 is also trained thru openings 27 and 28 in the partition 6. The outer ply of the belt 25 is provided with recesses 29 in which are disposed fingers 30 having the upstanding hooked end portions 31, which project a little above the outer surface of the outer ply. Openings 29' are provided in the inner ply of the belt 25 one registering with each recess 29. These fingers 30 are secured to the inner ply of the belt. The fingers are arranged in pairs and as the belt moves through its orbit, these fingers engage one of the plates 13 to move it along with the belt. Only one plate will be moved at a time, a stop 32 being provided for this purpose.

A plurality of return address plates 33 are mounted on the outer ply of the belt, one adjacent each pair of fingers 30. Two series of inking rolls 34 and 36 are provided respectively for the plates 13 and plates 33. The inking roll of each series has flanges 36' which ride on the outer ply of the belt. The outer ply is provided with slots 35' adjacent plate 33 and fingers 30 so 90 that the rolls will lower as the flanges move in the slots to engage the plates 33 and 13.

At the bottom of each hopper 9 there is disposed a shield plate 35, having an upturned edge 37. A pair of spaced lugs 38 project from each side edge of the plate 35 for receiving therebetween a stop pin 39 projecting from the hopper 9. The envelopes 11 rest on this plate 5 so as to be out of engagement with the belt 25. A pair of longitudinally extending slots 40 extend from those points spaced rearwardly from the upturned edge 37 to the rear edge of the shield plate 35. These slots 40 are disposed so as to receive the hooks 31 of the fingers 30 for the purpose of engaging the bottom envelope in the hopper 9. A resilient stop

37' is disposed at the bottom of the hopper 9 and allows the ejection of the envelope one at a time only.

In order to engage the bottom envelope of the hopper 9, it will be seen that said envelope must be first pushed rearwardly to some extent and for this purpose I provide a pair of friction rolls 42, each including a relatively small disk 43 and a relatively large disk 44. The belt 25 is provided with slots 45 to the rear of each pair of fingers 30. The rolls 42 are mounted on shafts 46 journaled in spring pressed bearings 47. Normally the disks 44 are in engagement with the inner ply of the belt 25, but as this belt moves and the slots 45 come along, the large disk 44 projects through the slot to engage the bottom envelope, and at the same time the smaller disks 43 engage the inner ply of the belt so that the rolls are turned and the larger disk causes the bottom envelope to move into a position for being engaged by the next pair of hooks 31 of fingers 30 as will be apparent from an inspection of Fig. 2.

A spring pressed platen roller 48 has its shaft mounted in spring supported bearings 49 and presses the envelope against the plates 13 and 33 so that the forwarding address and the return address will be printed thereon simultaneously. The envelope will be ejected through the opening 50 in the cover portion 8 of the casing.

The present embodiment of the invention has been disclosed merely in detail by way of example, since in actual practice it attains the features of advantage enumerated as desirable in the statement of the invention and the above description. It is apparent, however, that numerous changes in the details of construction, and in the combination and arrangement of parts may be resorted to without departing from the spirit or scope of the invention as hereinafter claimed or sacrificing any of its advantages.

Having thus described my invention, what I claim as new is:

1. In an addressing machine of the class described, an endless belt trained to move through a predetermined orbit, engaging

means on the belt and spaced at intervals, a hopper for containing a plurality of printing plates to be ejected therefrom one at a time by said engaging means, a second hopper adapted to contain a plurality of envelopes, a plate at the bottom of the second hopper, said plate provided with longitudinally extending slots for receiving the engaging means and means for disposing the bottom envelope in the second hopper so as to be in a position for ejection by said engagement means.

2. In an addressing machine of the class described, an endless belt trained in a predetermined orbit, a plurality of engaging fingers mounted on the belt and arranged in spaced pairs, means for feeding printing plates to said engaging means, an envelope hopper, a shield plate at the bottom of the envelope hopper having a forward upturned edge provided with longitudinally extending slots starting a distance rearwardly of the upturned edge, and openings at the sides thereof, said belt provided with slots in advance of the fingers, rollers projectible through the slots in the belt to engage the bottom envelope in the hopper and partially eject the same so as to be engaged by the oncoming fingers.

3. In an addressing machine of the class described, an endless belt trained in a predetermined orbit, a plurality of engaging fingers mounted on the belt and arranged in spaced pairs, means for feeding printing plates to said engaging means, an envelope hopper, a shield plate at the bottom of the envelope hopper having a forward upturned edge provided with longitudinally extending slots starting a distance rearwardly of the upturned edge, and openings at the sides thereof, said belt provided with slots in advance of the fingers, rollers projectible through the slots in the belt to engage the bottom envelope in the hopper and partially eject the same so as to be engaged by the oncoming fingers, and printing means for pressing the envelope against the plate.

In testimony whereof I affix my signature.

OVILA J. VERRETT.
